FIG. 3

FIG. 4

FIG. 5FIG. 6FIGURE 1 is a top plan view of a video tape recorder or similar article, showing my new design;

FIGURE 2 is a front elevational view thereof;

FIGURE 3 is a rear elevational view thereof;

FIGURE 4 is a left side elevational view thereof;

FIGURE 5 is a right side elevational view thereof; and

FIGURE 6 is a bottom plan view thereof.

The perforations indicated by dots in FIGURES 2 and 4 are continuous within the area indicated.

The dominant features of my design reside in the portions shown in full line.

I claim:

The ornamental design for a video tape recorder or similar article, substantially as shown and described.
